UNITED STATES PATENT OFFICE

2,577,909

AUTOMATIC STOP DEVICE FOR MOTION-PICTURE PROJECTORS

Peter S. Nielsen, Bismarck, N. Dak.

Application May 25, 1949, Serial No. 95,251

1 Claim. (Cl. 200—52)

1

This invention relates to an automatic stop device for motion picture projectors.

It is an important object of the invention to provide a means for automatically stopping the motor of a projector when a film break occurs which will be simple, sure, and swift in its operation.

Another important object of the invention is to provide a device of the type stated which can be installed in a conventional motion picture projector without necessity of modification of the projector construction, and without affecting in any way the normal operation of the projector or the normal arrangement of the components parts of the projector.

Another important object is to provide a device of the type stated which will be constructed with a minimum of parts simply arranged, will occupy a minimum of space, and will be capable of being sold and installed at low cost.

With the foregoing and other objects in view which will appear as the description proceeds, the invention consists of certain novel details of construction and combinations of parts, hereinafter more fully described and pointed out in the claim, it being understood that changes may be made in the construction and arrangement of parts without departing from the spirit of the invention as claimed.

Referring to the drawings

Fig. 1 is a sectional view through a portion of a projector showing, in side elevation, the automatic stop device of the invention.

Fig. 2 is a perspective view, portions being broken away, of the main portion of said device.

Referring to the drawings in detail my automatic stop device is mountable in a conventional motion picture projector including a front wall 5, bottom plate 6, rear wall 7, main drive shaft 8, and lower take-up sprocket 9 over which is threaded the film 10.

The invention includes a stationary supporting bracket 11 readily stamped from a suitably shaped metal blank and formed at one end with the upturned transverse flange 12 adapted to be positioned against the inner surface of the front wall 5 as clearly shown in Fig. 1, and formed with the spaced openings 13 through which extend the fastening means 14 for securing said bracket firmly and immovably to the front wall.

The intermediate portion of the bracket 11 can be supported upon underlying portions of the bottom plate 6, and the other end of the bracket 11 is extended to partially overlie the usual bottom opening formed in the plate 6, through which

2

the film 10 passes, said other end of the bracket 11 being formed with the hinged portion 15 adapted to be aligned with hinged portions 16 formed on one end of the swinging arm 17 also capable of being readily stamped to shape from a suitable metal blank. Hinge pin 18 extends through the aligned cooperating hinged portions 15, 16 for the purpose of swingably mounting the arm 17 upon the stationary bracket 11. Intermediate its ends the arm 17 is integrally formed with the spaced spring wings 18' having at their free ends the inwardly extended clamping portions 19. The portion of the arm 17 that is disposed between the wings 18' is outstruck to provide an inclined tongue 20 which is bent to a desired angle of inclination relative to the arm 17, as shown particularly in Fig. 1. As seen from the drawings, the clamping edge portions, being pressed inwardly, overhang the side edges of the tongue 20 in any selected position of angularity to which the tongue is adjusted relative to the arm 17, so as to grip a mercury switch, to be described hereinafter, to hold it against the tongue in longitudinal contact with the tongue, thereby causing the mercury switch to assume the same position of angularity relative to the arm 17 as is assumed by the tongue. In each selected position of adjustment of the tongue, the spring wings 18' are proportioned and located to constitute side walls that hold the mercury switch against lateral shifting off the tongue, in any adjusted position of the tongue.

The free end of the arm 17 is transversely curved at 21 to provide a contact surface with the film 10 that will reduce frictional contact between the arm 17 and the film 10 to a minimum.

As may be noted, both the supporting bracket 11 and the swinging arm 17 can be formed from single blanks of sheet metal capable of being die stamped in quantity to the desired shapes.

A mercury switch 22 is pressed against the tongue 20 and is disposed between and clamped by the spring wings 18' and clamping portions 19, so that said mercury switch 22 is secured to the arm 17 at the same angle of inclination as the tongue 20.

Extending from the mercury switch 22 are the leads 23, 24 which are preferably secured to the bracket 11 as by a hold-down clamp 25, and said leads are then extended through a suitable opening formed in the front wall 5. One of the leads can have, exteriorly of the projector, the manually operated main switch 26, while the other lead extends to the motor 27, said switch and motor being in circuit with each other and with the switch

22 and extending to the ordinary house supply 28. I believe the use of the automatic stop device will be readily apparent. Assuming that the device has been mounted as shown and described, the arm 17 is elevated to the full line position illustrated, in which position it is supported at a slight angle of inclination from the vertical, being held in said slightly inclined position by the film 10 as the film runs through the projector in normal operation of the projector.

Should a film break occur, the arm 17 will immediately drop to the dotted line position illustrated in Fig. 1, and this will automatically position the mercury switch 22 to break the circuit to the motor 27, thus to stop projector operation immediately and before the film can pile up or cause a film fire.

What is claimed is:

In an automatic stop device for motion picture projectors, a supporting bracket of one-piece construction formed from a length of wide flat material, one end of said bracket being adapted for fixed connection to a motion picture projector with the remaining portion of the bracket extending laterally and horizontally interiorly of the projector and in the plane of film running through the projector, the other end of said bracket being integrally formed with a horizontally disposed hinge portion; a swinging arm integrally formed from a single piece of flat material of the approximate width of and in the plane of the film and of said supporting bracket, said arm being integrally formed at one end with a hinge portion cooperating with the hinge portion of the supporting bracket and hingedly connected to the first-named hinge portion for vertical swinging of said swinging arm, said swinging arm being formed at its other end with a curved film-contacting portion for supporting of the swinging arm in a substantially upright position when film is running through the projector, said film normally maintaining said swinging arm against gravitational downward swing-

ing, the swinging arm being formed between said film-contacting and hinge portions with an intermediate clamp portion, said clamp portion including a pair of spring wings extending longitudinally of said swinging arm and in a direction away from said film, said clamp portion including a tongue disposed between said spring wings, the spring wings and tongue being integrally formed out of the material of the swinging arm, the spring wings having edge portions extended inwardly toward each other, said tongue being pressed outwardly out of the plane of the swinging arm proper, the tongue being connected to the swinging arm at one end only of the tongue and being bendable to selected positions of angularity relative to the arm; and a mercury switch clamped between said edge portions of the spring wings and held by said edge portions in longitudinal contact with said tongue, whereby to assume the same position of angularity to the arm as is assumed by the tongue, the edge portions being proportioned to extend outwardly from the arm a substantial distance beyond the tongue to overhang and be spaced above the side edges of the tongue in each selected position of bendable adjustment of the tongue, said spring wings constituting side walls located at opposite sides of the switch when the switch is clamped between the tongue and edge portions, to retain the switch against lateral shifting off the adjustably positioned tongue.
